UNITED STATES PATENT OFFICE.

LEOPOLD LISSE, OF BERLIN, GERMANY.

METHOD OF PRODUCING BLASTING CARTRIDGES CAPABLE OF ABSORBING LIQUEFIED GASES.

No Drawing.

Application filed July 19, 1920. Serial No. 397,552.

To all whom it may concern:

Be it known that I, LEOPOLD LISSE, Berlin, Konigin-Augustastrasse 43, in the State of Prussia and German Empire, have invented certain new and useful Methods of Producing Blasting Cartridges Capable of Absorbing Liquefied Gases, for which I have filed an application in Germany January 4th, 1915 (V. 12943 IV/78e), Franz Volpert, and of which the following is a specification.

The present invention relates to a method of manufacturing blasting cartridges in which liquid air is used as an oxidizing medium, and consists in shaping and uniting the carbonaceous and other explosive constituents so as to form a caseless, porous cartridge body adapted to absorb the liquid air or oxygen necessary for its explosion.

In the manufacture of the cartridge a mixture is made out of soot or some other carbonaceous substance, an adhesive binding agent such as castor-sugar, resin, bran or the like, a ferment such as yeast or bicarbonate of soda, and enough liquid to make a paste. This paste is pressed into the desired shape and baked until a rigid porous body is obtained, the porosity being obtained by the action of the ferment. Instead of forming complete cartridges, the paste may be formed into discs, rings or rods which are subsequently assembled so as to form cartridges of the required size.

In cases when cheapness and rapidity of manufacture are of consequence, the cartridge can be made of a carbonaceous substance which is in itself porous, for instance sawdust, peat or the like, such substance being made together with a binding agent into a paste out of which the cartridges, complete or in parts, are shaped and dried to form rigid porous structures. The shapes may be enclosed in a wrapper.

Cartridges of this kind of more or less highly explosive character can also be made out of wood fibre, bast, wool, hemp cotton, paper, jute, linen and like carbonaceous fibrous materials in torn, ground, spun, woven, twisted or braided form. Suitable round, angular or otherwise shaped bodies

made out of these materials can be bundled together and tied with strings or the like, with or without adhesives, to form cartridges. Compressed pieces of wood, plant materials, sawdust, wood-wool, various kinds of string or rope, either singly or bundled may be used to make cartridges. Before or after the impregnation with liquid air, these materials may either be mixed with or impregnated with solutions of substances which, either while in solution or when dry, increase or diminish the rapidity of the charge. For instance, to reduce the sensitiveness of the charge, so as to prevent it from causing the explosion of coal-dust and fire-damp, an addition thereto of water, common salt, soap, sugar and the like will prove effective.

I claim:—

1. A method of manufacturing liquid air blasting cartridges consisting in shaping and uniting the carbonaceous and other explosive constituents so as to form a caseless, porous cartridge body capable of absorbing the liquid air or oxygen necessary for its explosion.

2. A method of manufacturing liquid air blasting cartridges consisting in adding to the porous carbonaceous and other explosive constituents an adhesive binding agent, and uniting and shaping such constituents so as to form a caseless cartridge element capable of absorbing the liquid air or oxygen necessary for their explosion.

3. A method of manufacturing liquid air blasting cartridges consisting in mixing powdered carbonaceous substances, a means capable of slowly evolving gases comprising a binding agent, and enough liquid to make a paste, shaping such paste into caseless cartridge elements, and baking such elements so as to form rigid porous bodies capable of absorbing the liquid air necessary for their explosion.

4. A method of manufacturing liquid air blasting cartridges consisting in adding to the carbonaceous explosive and other constituents a substance rendering the charge safe against reaction with coal-dust and fire.

damp, and then baking and uniting the constituents so as to form a caseless porous cartridge body capable of absorbing the liquid air necessary for its explosion.

5 5. A method of manufacturing liquid air blasting cartridges consisting in bundling together vegetable materials so as to form caseless cartridge elements capable of ab-

sorbing the liquid air necessary for their ex-
plosion.

In testimony whereof I affixed my signature in the presence of two witnesses.

LEOPOLD LISSE.
